PORTABLE, COLLAPSIBLE STOVE

John E. Delahoussaye, Lafayette Parish, La.
(103 Octahoula, Lafayette, La. 70501)

Filed Sept. 5, 1972, Ser. No. 286,066

Term of patent 14 years

Int. Cl. D7—02

U.S. Cl. D7—110

FIG. 1.

FIG. 2.

FIG. 3.

FIG. 4.

FIG. 5.

FIG. 6.

FIG. 1 is a perspective view of the portable stove of the present invention in its erected position, showing the front, sides and top of the new design;

FIG. 2 is a top view of the portable stove of FIG. 1 on a reduced scale; and

FIG. 3 is a side view of the portable stove of FIG. 1 on a reduced scale, both sides being substantially identical; while

FIG. 4 is a perspective view of the portable stove of the present invention in its collapsed position, showing the front, sides and top of the new design;

FIG. 5 is a top view of the portable stove of FIG. 4 on a reduced scale; and

FIG. 6 is a side view of the portable stove of FIG. 4 on a reduced scale, both sides being substantially identical.

I claim:

The ornamental design for a portable, collapsible stove, as shown and described.
